Specification for Design.

Patented Feb. 7, 1922.

Application filed July 1, 1921. Serial No. 481,960. Term of patent 14 years.

To all whom it may concern:

Be it known that I, EDWIN C. MORINE, a citizen of the United States, residing at Detroit, in the county of Wayne and State of Michigan, have invented a new, original, and ornamental Design for Vehicle Cabs, of which the following is a specification, reference being had to the accompanying drawing, forming part thereof.

The figure is a perspective view of a vehicle cab showing my new design, the parts of the vehicle adjacent thereto being shown in dotted lines.

I claim:

The ornamental design for a vehicle cab, as shown.

EDWIN C. MORINE.
